UNITED STATES PATENT OFFICE.

ALBERT F. SCHROEDER, OF CLEVELAND, OHIO.

SHERARDIZING APPARATUS.

933,725.

Specification of Letters Patent. Patented Sept. 7, 1909.

Application filed July 2, 1909. Serial No. 505,656.

To all whom it may concern:

Be it known that I, ALBERT F. SCHROEDER, citizen of the United States, residing at Cleveland, in the county of Cuyahoga and State of Ohio, have invented certain new and useful Improvements in Sherardizing Apparatuses, of which the following is a specification.

This invention relates to sherardizing apparatuses, and has for its object to provide an improved apparatus for practicing the sherardizing process in a more economical and efficient manner than has been heretofore possible.

In the use of my invention in the practice of this process, the articles to be sherardized are first freed from all extraneous matter in any well known way and are then placed in suitable metallic barrels or drums together with a quantity of zinc dust. These barrels or drums are provided with removable portions to permit of placing the material to be treated therein and removing it therefrom. The removable portions are preferably so secured in place that a substantially airtight joint is formed between them and the walls of the barrels or drums. The barrels or drums with their contents are then moved into a heating chamber preferably a furnace and heated to the desired temperature for the desired length of time after which they are withdrawn and allowed to cool. While in the furnace, the barrels or drums are revolved either continuously or periodically to thoroughly bring the zinc dust into contact with the material to be sherardized. When the barrels or drums are removed and opened, they are rotated to discharge the material, the zinc dust and coated articles being simultaneously discharged. The latter operation formerly resulted in quite a loss of the zinc dust but means are provided in my apparatus to confine the dust and separate the same from the coated articles without loss.

In the accompanying drawings, which illustrate my invention, and form a part of this specification, Figure 1 is a side elevation thereof, showing the dust hood raised. Fig. 2 is an end elevation of the wheeled frame, and Fig. 3 is a longitudinal vertical sectional view through the apparatus, shown in Fig. 1, with the dust hood lowered.

In accordance with my invention, I provide a dust receptacle 1, embodying an upper screen 2, mounted between the outer ends of

rails 3, which latter extend into a furnace, 55 not shown.

A frame comprising a rectangular body 4, is provided with transverse shafts 5, journaled through said body 4, transversely and adjacent the ends thereof, which shafts have 60 wheels 6, secured upon their outer ends to travel upon the rails 3, and are provided centrally within the body 4, with worm wheels 7, secured thereon. The body 4 is also provided with a shaft 8, journaled centrally and 65 longitudinally thereof, and above shafts 5, which shaft 8 is provided with worms 9 in engagement with the worm wheels 7 of shafts 5, whereby the rotation of shaft 8 by a suitable crank upon its outer squared end 10, 70 serves to impart rotation to shafts 5, and cause travel of the frame upon rails 3. Standing from the side members of body 4, are a series of transversely aligned brackets 11, supporting between their upper ends, 75 blocks 12, through which the end trunnions 13 of the horizontal axially rotatable barrels 14 are journaled. These barrels have removable portions 15 bolted thereto, and constituting doors for the intake and outlet of the 80 material to be sherardized and the zinc dust. The trunnions 13 at one side of the frame are provided with worm wheels 16, with which engage worms 17 secured upon a longitudinal shaft 18, journaled upon the respective side brackets 11, which shaft 18 has a squared outer end 19, with which the inner squared socket end 20 of a shaft 21 may engage to simultaneously rotate the barrels 14 85 when the frame has been rolled within the 90 furnace, said shaft 21 extending outwardly of the furnace, and being thus adapted for manual rotation.

When the wheeled frame is withdrawn from the furnace, it is drawn to the position 95 shown in the drawings, over the dust receptacle 1, and doors 15 are unbolted and removed when the said doors are uppermost. A dust shield 22 is then lowered from the wheeled frame, said shield being rectangular 100 in form as shown, and opening downwardly, and may be suitably mounted for vertical movement by its ropes 23 extending upwardly from eye-bolts 24 in its top. The barrels are then rotated to the position 105 shown in Fig. 3, and the contents thereof dumped upon the upper screen 2 of the dust receptacle 1, which screen catches the sher-

ardized articles, and permits the settling dust to pass therethrough into the receptacle 1 below the screen. Thus, it will be seen by the employment of my improved apparatus, 5 in carrying out the process of sherardizing, the work may be prepared in an efficient and economical manner.

Having fully described my invention, I claim:

10 1. In an apparatus of the character described, the combination of a wheeled traveling frame, a plurality of barrels rotatively mounted thereon and embodying removable portions, and means to simultaneously rotate said barrels, embodying a member adapted to extend out of a furnace when the frame is located therein.

2. In an apparatus of the character described, the combination of a wheeled traveling frame, shafts journaled therein upon which said wheels are secured, a rotatable barrel mounted in said frame, worm wheels on said wheel shafts, and a shaft journaled in said frame transversely across said wheel shafts, having worms in engagement with the said worm wheels.

3. In an apparatus of the character described, the combination of a dust receptacle, a wheeled frame for travel thereover, a rotatable barrel mounted in said frame and embodying a removable portion, and a dust hood to cover said frame and barrel when the same is over said dust receptacle.

4. In an apparatus of the character described, the combination of a dust receptacle embodying an upper screen, rails between which said receptacle is mounted, a wheeled frame for travel upon said rails above said receptacle, rotatable barrels journaled in said frame, and embodying removable portions, and means to simultaneously rotate said barrels.

5. In an apparatus of the character described, the combination of horizontal axially rotatable barrels embodying removable portions, and gearing connecting said barrels for simultaneously rotating the same.

6. In an apparatus of the character described the combination of horizontally axially rotatable barrels, embodying removable portions, means for simultaneously rotating said barrels, and a dust hood to cover said barrels when the same are rotated to discharge their contents.

55 7. In apparatus of the character described, the combination of a traveling support adapted to be moved into a heating chamber, a container mounted on said support, said container being adapted for movement to effect a thorough mixing of the contents thereof and said container being provided with an opening for the admission and removal of the material to be treated, a closure for said opening and means extending without said heating chamber to impart

movement to said container to effect the thorough mixing of its contents when said support and container are located in said heating chamber.

8. In apparatus of the character described, 70 the combination of a traveling support adapted to be moved into a heating chamber, a container rotatably mounted on said support and provided with an opening for the admission and removal of material to be treated, a closure for said opening and means extending without said heating chamber to effect the rotation of said container when said support and container are located in said traveling chamber. 75

9. In apparatus of the character described, the combination of a traveling support adapted to be moved into a heating chamber, a container mounted on said support, said container being adapted for movement to effect a thorough mixing of the contents thereof and said container being provided with an opening for the admission and removal of the material to be treated, a closure for said opening, a dust receptacle 80 adapted to receive dust from said container and a dust hood adapted to cover said container when the dust therein is being discharged into said dust receptacle. 85

10. In apparatus of the character described, the combination of a traveling support adapted to be moved into a heating chamber, a container mounted on said support, said container being adapted for movement to effect a thorough mixing of the contents thereof and said container being provided with an opening for the admission and removal of the material to be treated, a closure for said opening, a dust receptacle 90 adapted to receive dust from said container and a screen above said receptacle adapted to catch and hold treated articles discharged from said container and permit the dust in said container to pass therethrough. 95

11. In apparatus of the character described, the combination of a traveling support adapted to be moved into a heating chamber, a container mounted on said support, said container being adapted for movement to effect a thorough mixing of the contents thereof and said container being provided with an opening for the admission and removal of the material to be treated, a closure for said opening, a dust receptacle 100 adapted to receive dust from said container, a screen above said receptacle adapted to catch and hold treated material discharged from said container and permit dust contained therein to pass therethrough and a dust hood adapted to cover said container 105 when the contents thereof is being discharged upon the said screen. 110

12. In apparatus of the character described, the combination of a traveling support adapted to be moved into a heating 115

chamber, a container rotatably mounted upon said support and provided with an opening for the admission and removal of material to be treated, a closure for said 5 opening, means to rotate said container when said support and container are in said heating chamber, a dust receptacle located in the path of movement of and below said support and adapted to receive dust from said 10 container and a dust hood adapted to cover

said support and container when dust is being discharged from the latter into said dust receptacle.

In testimony whereof I affix my signature in presence of two witnesses.

ALBERT F. SCHROEDER.

Witnesses:

LEONARD W. SMITH,
R. B. DANGELESSEN.

It is hereby certified that in Letters Patent No. 933,725, granted September 7, 1909, upon the application of Albert F. Schroeder, of Cleveland, Ohio, for an improvement in "Sherardizing Apparatus," an error appears in the printed specification requiring correction, as follows: In line 80, page 2, the word "traveling" should read *heating*; and that the proper correction has been made in the files and records of the Patent Office, and is hereby made in said Letters Patent.

Signed and sealed this 12th day of October, A. D., 1909.

[SEAL.]

C. C. BILLINGS,

Acting Commissioner of Patents.
